INVENTOR:
FREDERICK F. BRUSH,
BY
Graham + Harris
ATTORNEYS.

UNITED STATES PATENT OFFICE.

FREDERICK F. BRUSH, OF LOS ANGELES, CALIFORNIA, ASSIGNOR TO ELEVATOR SAFETY APPLIANCE COMPANY, A CORPORATION OF CALIFORNIA.

ELEVATOR-DOOR-OPERATING MECHANISM.

Application filed April 11, 1923. Serial No. 631,380.

To all whom it may concern:

Be it known that I, FREDERICK F. BRUSH, a citizen of the United States, residing at Los Angeles, in the county of Los Angeles 5 and State of California, have invented a new and useful Improvement Comprising an Elevator-Door-Operating Mechanism, of which the following is a specification.

My invention relates to devices for opening and closing elevator doors by means of a mechanism carried on the car, this mechanism being used when the car arrives at any floor to operate the door at that floor. To accomplish this result, it is necessary to 10 provide a projection or projections on the door or connected with the door which are engaged by operating fingers carried on the car. Inasmuch as an elevator car does not move in exact alinement in its shaft, it is further necessary that considerable clearance be allowed between the projections and the fingers as they come into operative 15 relationship, and that this clearance be taken up by closing the fingers in on the projection before starting to open the door, the fingers being opened again at the end 20 of the closing movement of the door.

The principal object of my invention is to provide novel means for insuring the 25 opening and closing of these fingers to produce and destroy this clearance.

Referring to the drawings which are for 30 illustrative purpose only, Fig. 1 is a somewhat diagrammatic view of my invention 35 with the parts in the position they assume with the doors in their closed position and the car free to move in the building structure.

Fig. 2 is a similar view, the full lines 40 showing the mechanism in the position it assumes with the door fully open. Certain portions are also shown in dotted lines in the position they assume at the beginning 45 of the opening and finish of the closing movement before the fingers start to open to establish clearance.

Fig. 3 is a side view of the mechanism 50 shown in Fig. 2, and Fig. 4 is a section on a plane represented by the line 4—4 of Fig. 2.

The apparatus illustrated in these drawings comprise a frame 11 having a cylinder 12 rigidly secured thereto, a piston 13 being

fluid actuated by any convenient means, not shown, and moving freely in the cylinder 12. 55 The piston 13 operates a head 14 which slides in the frame 11. Any other convenient means of sliding the head 14 in the frame 11 may be substituted for the cylinder and piston shown, such for example 60 as motor driven devices of all kinds.

Mounted on the pins 20, carried on the head 14 is a closing finger 21 and mounted on a pin 22 is an opening finger 23, these fingers being normally pulled together by a 65 tension spring 24 into the position shown in Fig. 1. Limit plates 25 govern the distance these fingers can move together under the influence of the spring 24. Fingers 21 and 23 close down upon projections 30 and 31 70 sliding in a door operating and locking plate 32, the projections 31 and 32 being attached or connected to the door not shown. The finger 21 is connected through a walking beam 40 with a plunger 41 and the finger 23 75 is provided with a crank 50, the plunger 41 and the crank 50 projecting from the head 14 in such a manner that they strike against a closing plate 60 just before the door is entirely closed. 80

The method of operation of my invention is as follows:

The parts being in the position shown in Fig. 1, it will be noted that fingers 21 and 23 are withdrawn to a point within the limit 85 lines of the frame 11 and that they are held in this position due to the contact of the crank 50 and the plunger 41 with the plate 60.

It will also be noted that the fingers 21 and 90 23 are widely separated thus giving a great deal of clearance between these fingers and the projections 30 and 31. When it is desired to operate the door, the head 14 is actuated by means of the cylinder 12, the head 95 moving upwardly as viewed in the drawings. During its initial movement, the head 14 moves away from the plate 60 thus allowing the crank 50 and the plunger 41 to be forced downwardly under the influence of the 100 spring 24. As a result the fingers 21 and 23 close together into the position shown in dotted lines in Fig. 2. A further movement of the head 14 moves the projections 30 and 105 31 and various members not shown connected therewith which opens the door. The

2
fingers 21 and 23 maintain their close contact with the projections 30 and 31 until the door is nearly closed at which time the crank 50 and the plunger 41 strike against the plate 60 and the fingers are again opened.

5 I claim as my invention:

10 1. In an elevator door operating device; a frame; a head sliding in said frame; a door operating finger projecting from said head to engage a projection on the door; mechanism for sliding said head in said frame; and means for utilizing a portion of said frame to disengage said finger from said projection at or near the end of the door closing cycle.

15 2. In an elevator door operating device; a frame; a head sliding in said frame; a door operating finger projecting from said head to engage a projection on the door; mechanism for sliding said head in said frame; a spring holding said finger in its engaged position; and means by which a portion of said

frame throws said finger out of its engaged position.

20 3. In a door operating device; a frame; a head sliding in said frame; fingers projecting from said frame to engage a projection on the door; a spring for holding said fingers in their engaged position; and means for utilizing a portion of said frame to throw said fingers out of their engaged position.

25 4. In a door operating device; a frame; a head sliding in said frame; fingers projecting from said frame to engage a projection on the door; a spring for holding said fingers in their engaged position; and means by which a projection on said frame opens said fingers at one end of the movement of said head.

30 35 In testimony whereof, I have hereunto set my hand at Los Angeles, California, this 5th day of April, 1923.

40 FREDERICK F. BRUSH.
